Inventor:

P. Strüdel

UNITED STATES PATENT OFFICE

PATERNE STRÜDEL, OF HANOVER-LINDEN, GERMANY

UNRAVELING MACHINE

Application filed August 18, 1928, Serial No. 300,488, and in Germany August 24, 1927.

This invention refers broadly to the art of unravelling, disheveling or similarly treating woven, knitted and similar fabric for the purpose of loosening the threads and freeing them from their connection and for similarly treating goods of such kind by means of 5 combing or defibrating means to which the material to be treated is fed by means of fluted rollers or the like disposed in the cavity of the trough-shaped concave recessed portion of a plurality of adjacently disposed key-like bars or the like, sometimes called "spoons" and constituting a gutter-shaped trough running in parallelism with the combing or defibrating drum and above or below 10 the corresponding fluted roller, such keys or the like being usually spring-actuatingly arranged. Among other important objects the invention is intended to facilitate the operation 15 of the keys and their cooperation with the fluted rollers and the combing instrumentality, so that the manipulation of detaching the fibres from their connection in the weave is facilitated and a more satisfactory product with a lower percentage of 20 waste is obtained than it was generally possible heretofore.

In accordance with the broad features of my invention, these objects and other advantages are obtained by improving the operation 25 of the introducing means for the fabric to be treated by a system of compensating bars or the like provided on or attached to the spring-acting supports for the concave keys 30 or "spoons", the said bars being adapted to cooperate with preferably sharp-teethed or large-teethed fluted rollers which may be arranged below said bars and in cooperation 35 with the bars are adapted to determine the available size of the passage opening between the vertically displaceable concave keys and of the cooperating fluted roller above or 40 below the same. By this means the material to be treated is uniformly and smoothly fed to the combs or needles of the combing drum or the like.

It is a further object of my invention to provide means by which the supports for the concave keys are mounted adjacent each 45 other in a guide, so that they will mutually

rest against each other and mutually act as guides for the particular keys and for themselves, and are arranged in such a manner that after the removal of a front covering plate or the like the supports may be withdrawn singly for the purpose of exchange or repair. 55

The invention will be more particularly described by reference to the accompanying drawing showing by way of exemplification 60 a device embodying the leading features of my invention in a somewhat diagrammatic manner and in Fig. 1 in vertical section and in Fig. 2 in horizontal section on the line 65 2-2 of Fig. 1.

The several concaved keys ("spoons") 17 in the exemplification shown, are disposed above the fluted roller 16 and constitute together a trough-shaped, so-called "piano"-groove or operating slot 25. The supporting 70 bars 53 of the keys 17 are adjacently and slidably disposed in guides 54 and may be singly withdrawn after the removal of the closing plate 70. At their other ends the several supporting bars 53 are provided with a terminating stud 56^a surrounded by and supporting a compression spring 57 which at its other end rests against the head 71 and may surround a stud 56^b screw-threadedly secured 75 in the head 71. Each of the concaved bars 80 17 is provided at its front side with a compensating bar 72 which may be secured to the keys by screws 73. This bar 72 is provided with an upwardly inclined bottom surface 74 below which the fluted roller 75 is arranged. 85 This roller 75, as shown in the drawing, possesses comparatively large teeth which are of greater depth and sharper or more pointed than the teeth of the fluted roller 16. In front of the parts 74, 75 the usual introductory rollers 9, 10 are arranged. 90

The mode of operation of the device is substantially as follows:

The fabrics introduced into the machine by the rollers 9 and 10 are conducted against 95 the downwardly inclined surface 74 and are guided into the slot 74^a between the compensating bar 72 and the fluted roller 75. In view of the sharp configuration of their teeth the rollers cause the material to be re- 100

liably caught and fed towards the combing member 11, while the compensating bar 72 by means of its spring 57 is yieldingly adjusted in accordance with the nature of the material, whether large-pieced or small-pieced fragments of fabric or pieces of greater or smaller thickness are treated. The material is subsequently led into the slot 25.

The fluted roller 16 in the exemplification shown, runs at a larger rate than the fluted roller 75 and this latter roller rotates more quickly than the fluted rollers 9 and 10, so that the material reaches the point of operation in a stretched condition, which is a point of importance in facilitating uniform and substantially straight unraveling of the fabric. The machine may be so adjusted that every kind of tissue and of knitted fabrics may be reliably treated unraveled and de-composed into its thread constituents. The invention has been described herein in its broad features only and it is to be understood that it may find expression in other embodiments than those herein shown merely by way of illustration of its principles, and without thereby deviating from the scope and spirit of the invention, as expressed in the accompanying claims.

I claim:

50. 1. In the art of unraveling woven and knitted fabrics in combination a plurality of adjacently disposed spring-operating transversely concave key-bars, a fluted roller spacedly parallel with the concaved parts 35 of said bars, and inclined guiding means cooperating with the space between the roller and the concaved part, admitting means below the guiding means, operating means for the roller, and combing means cooperating 40 with said roller.
45. 2. In the art of unraveling woven and knitted fabrics in combination combing means, a rotatable fluted roller cooperating therewith, a plurality of adjacently disposed spring-acting keys, troughed portions on said keys, constituting a groove spacedly surrounding part of said roller, spring-acting supporting means for said keys, a downwardly inclined guide on said supporting 50 means opposite the combing means and fluted introducing means for the material below said inclined guide.
55. 3. In the art of unraveling woven and knitted fabric in combination combing means, a rotatable, substantially fluted roller cooperating therewith, a plurality of adjacently disposed spring-acting keys, adjacent concaved portions on said keys, constituting a groove running parallel with said roller and somewhat spaced therefrom, a downwardly inclined guide on said keys opposite the combing means, and a plurality of parallel, differently toothed rotatable, fabric-introducing rollers below said inclined guide.
60. 4. In the art of unraveling woven and

knitted fabrics in combination combing means, a rotatable substantially lengthwise extending fluted roller cooperating therewith, a plurality of spring-acting adjacently disposed keys, adjacent concaved portions on said keys, constituting a groove running in parallelism with said roller and somewhat spaced therefrom, a downwardly inclined guide on said keys opposite the combing means and a plurality of parallel toothed rotatable fabric-introducing rollers below said guide and increasing in speed in the direction of the combing means.

5. In the art of unraveling woven and knitted fabric in combination a plurality of vertically spring-acting transversely concaved adjacently disposed keys constituting a transverse groove, a rotatable roller in said groove and spacedly parallel therewith, combing means on one side of said roller, and a plurality of parallel toothed feeding rollers on the other side of the first-mentioned roller and increasing in speed towards the first-mentioned roller and of less angular velocity than the same.

6. In a device of the kind described, combing means, a transverse fluted roller cooperating therewith, a plurality of spring-acting adjacently disposed keys concaved around the roller and constituting a groove spacedly parallel with said roller, guiding means in common for said keys and supporting bars for the keys within said guiding means and a detachable closing and securing plate on said guiding means and adapted to secure the supporting bars in adjacent position.
